Application October 21, 1940, Serial No. 362,090

14 Claims. (Cl. 38—22)

This invention relates to improvements in pressing machines designed especially for pressing small flat articles such as handkerchiefs, napkins and the like, although many of the features of our improved press are useful for other purposes.

An object of the present invention is to provide an improved press of the turret type having a single stationary heated ironing head and a pair of beds or bucks movable by rotation of a turret frame from a dressing position in front of the operator to a pressing position beneath the heated head. Our invention provides improved automatic mechanism for rotating the turret frame, for causing pressing engagement of the head and bed and for timing the pressing operation. Other features include improved means for clamping a workpiece on the bed for a smoothing or dressing operation, manual control of the automatic mechanism when desired, and improvements in the operating and control mechanism as will appear from the accompanying specification and drawings.

In the drawings, Fig. 1 is a side elevation of a press embodying our improvements, the same being broken away in section and showing the mechanism in an idle position; Fig. 2 is a rear elevation of the same machine showing the mechanism in idle position; Fig. 3 is an enlarged fragmental view of a part of the operating mechanism shown in Fig. 2 and with a bed raised to pressing position; Fig. 4 is a fragmental sectional view taken on the line 4—4 of Fig. 3, showing a portion of the turret frame in dash-dot lines to indicate its relation to the mechanism; Fig. 5 is a sectional view taken along the line 5—5 of Fig. 1; Fig. 6 is a fragmental sectional view taken on the line 6—6 of Fig. 5; Fig. 7 is a fragmental view of the manual and regulating valve mechanism looking in the direction of the arrows 7—7 of Fig. 9; Fig. 8 is a sectional view taken on the line 8—8 of Fig. 4 with coacting parts shown in dot-dash lines; while Fig. 9 is a diagrammatic view of the control mechanism and circuits.

The machine here disclosed comprises a main frame having a base member 10, side walls 11 and a top frame casting 12. Mounted on the top frame casting are two rear posts 13 and a forward post 14 about which the turret frame revolves. These three posts support a stationary head 15 which may be heated in any suitable or usual manner. The post 14 as best seen in Fig. 5 centers a turret frame bracket 16 which is supported on a suitable bearing 17 in the frame

5 casing 12. A turret frame 17 is mounted on the member 16 and extends in diametrically opposite directions for the support of a pair of pressing beds 18 and 19. Obviously, upon rotation of the turret frame one of the beds is carried into pressing position beneath the head 15 while the other bed is in dressing position in front of an operator.

10 Improved clamping means is provided for holding the rear edge of an article, such as a napkin or handkerchief, while the operator smooths the article on the pressing bed. This mechanism comprises two clamps 20, one for each bed and exactly alike so that one only need be described. Referring to Figs. 1, 5 and 6, each clamp extends 15 substantially the entire width of its associated bed and is pivotally mounted by arms 21 on a pair of brackets 22 supported by the turret frame. A link 23 connects one of the arms 21 with a lever 24 which is pivotally supported at 25 by a bracket 20 mounted on the turret frame. A spring 26 normally biases the clamps away from clamping position as shown in full lines in Figs. 1 and 6. An arcuate plate 24a is provided on the bottom of each lever 24 for engagement of the clamp actuating mechanism. Only one mechanism is provided and this comprises a rod 27 mounted for vertical movement in a block 28 and normally held in position to engage against one of the plates 24a associated with the clamp for that pressing bed which is in the forward or dressing position. The rod 27 is normally biased downwardly by a spring 29 held between the block 28 and a collar on rod 25. A pedal 30 carried by the frame is actuated by the foot of the operator to cause movement of a clamp to the dot-dash position of Figs. 1 and 6 when the operator desires to dress an article on the bed before her. The block 28 is so mounted as to take care of accidental operation of the pedal 30 before one of the clamp actuating plates 24a is in proper position above the rod 27. To this end the block 28 is movable horizontally between flanges 31 and the block is normally held in its rearmost position as indicated in full lines in Fig. 6 by a spring 32. If the rod 27 has been elevated by the operator before a pressing bed reaches proper position before her, the lever 24 will kick the rod 27 to the forward dash line position indicated in Fig. 6. The operator will then release the pedal 30 to return the rod to the full line position of Fig. 6 ready to perform the proper clamping operation as indicated by the dot-dash lines of that view.

15 The means provided for rotating the turret frame comprises a lever 33 which is rotatably mounted upon a stub shaft 34 carried by a

bracket 35 which is mounted on the top frame casting 12. The lever 33 has an upstanding branch 33a adapted to engage one of two projections 36 on the turret frame as will be presently described. The lever 33 has a downwardly extending branch 33b which is pivotally connected with the piston rod 37a of motor 37 whose cylinder 37b is pivotally mounted in the frame at 38. Another branch 33c of lever 33 is engaged by a pair of springs 39 which are connected to the main frame in a manner to bias the lever 33 in a counterclockwise direction as viewed in Fig. 2. A shock pad 40 on bracket 35 limits the movement of lever 33 in one direction and an adjustable screw or stop 41 limits its movement in the opposite direction. As best seen in Fig. 8 the upper end of lever arm 33a carries a spring pressed plunger 42 adapted to pass by the projection 36 when moving in one direction and adapted to engage that projection to turn the turret frame in the opposite direction. Also on the upper end of lever arm 33a is a pair of ears 43 between which is mounted a latch pin 44. When the motor 37 has moved the lever 33 clockwise from the position of Fig. 2 to the position shown in Fig. 3, the pin 44 engages behind a latch 45. This latch has an arm 45a which is connected by spring 46 to the frame so as to bias the latch 45 in an upward direction. A stop 47 limits this latch movement. A block 48 connected with latch 45 lies beneath a pin 49 of the bed in pressing position so that when that bed moves downwardly out of pressing position the pin 49 will engage the block 48 and release the latch 45 so that the turret frame may be rotated by the springs 39 acting on lever arm 33a which engages the projection 36 of the turret frame.

The beds 18 and 19 are each mounted for vertical movement relative to the turret frame 17. Each bed normally rests upon the turret frame on four corner posts 50. A pin 51 connected with the bed extends downwardly through a guiding bracket 52 in the turret frame. Another bracket 53 serves to guide the pin 49 and a spring 54 normally urges the pin and bed downwardly at this point. At the end of each bed toward the central post 14 is provided a flat leaf spring 55, which as best seen in Fig. 5 extends transversely of the bed and is connected at one end to the turret frame and at the other end to a boss 55a. This anchors the end of the bed to which it is attached and also helps to urge the bed downwardly out of pressing engagement with the head 15. Each bed in its central portion is provided with a downwardly extending bracket 56 adapted to be engaged by the actuating member of a motor 57 which is provided to cause pressing engagement between the head 15 and a bed in registry beneath it.

Means is provided for snubbing the movement of the turret frame as a bed moves into registration beneath the pressing head. One such means comprises a lever 58 connected to an air check cylinder 59. The lever 58 as shown in Figs. 1 and 2 is mounted on a stub shaft 60 which is carried by bracket 35. The upper end of this arm is connected by rod 61 to the piston of the air check 59. Exhaust from the air check is controlled by adjustable valve 62. The upper end of lever 58 carries a pin 63 which is adapted to be engaged by pin 51 as the turret frame moves to carry a bed into pressing position. This moves the lever 58 from the position shown in Fig. 3 to that shown in Fig. 2 so that the air check provides the desired snubbing action. When lever

5 arm 33a moves in a clockwise direction as seen in Figs. 2 and 3, a lug 64 carried by lever arm 33a engages pin 63 so as to return lever 58 to the position of Fig. 3 ready for its next snubbing operation. Additional means for providing snubbing action of the rotating frame and for holding the bed in registered position beneath the pressing head is best seen in Fig. 4. Here a lever 65 is pivotally mounted at 66 on the main frame for movement in a horizontal direction. This lever has a curved face 65a eccentric to the path of movement of the pins 51 as the turret frame revolves. The lever 65 is biased to the position shown in Fig. 4 by a spring 67 which is controlled by an adjusting screw 68 mounted in a bracket in the frame. Thus as one of the beds moves to registration position the pin 51 cams the lever 65 downwardly as viewed in Fig. 4 providing additional snubbing action to frame movement until pin 51 moves into notch 69 of lever 65 to hold the bed in registering position. A stop 70 on the frame limits the movement of lever 65.

Means is provided for moving a bed in registering position into pressure engagement with the head 15. This means comprises the motor 57 previously described whose cylinder 57a is mounted on the frame member 12. A piston 57b is normally biased downwardly by a spring 57c and is provided with a piston rod 57d adapted to engage against the bracket 56 of a bed directly above it. Pressure fluid is supplied to this motor as best seen in Fig. 9 from a supply conduit 71 through an operator controlled valve 72, conduit 73, a valve 74 controlled by turret frame rotation, conduit 75, valve 76 controlled by a timer, and conduit 77. Valve 76 is normally open as shown in Fig. 9 and its operation by the timer will be later described. Valve 74 is normally closed and is opened by movement of a pressing bed into registration position beneath the pressing head 15. The means provided for accomplishing this includes a spring pressed plunger 78 pivotally mounted at 79 on a bracket connected with the frame. A rotatable follower 80 on the plunger mechanism is engaged by a finger 81 as a bed reaches registering position. It will be noted in Fig. 1 that there are two of these fingers, one located beneath each bed on the turret frame.

The timer mechanism as best seen in Fig. 9 comprises a reservoir 82 adapted to be filled with pressure fluid through the branch 71a of conduit 71 which leads to a needle control valve 83 located within reach of the operator and thence by way of conduit 84 to the reservoir 82. The upper end of this reservoir is closed by a diaphragm 85 which is adapted to move upwardly and engage a stem 86 which in turn is adapted to lift valve 87 from its seat when the lifting force overcomes the pressure in the diaphragm chamber 88 which acts through spring 89 to hold valve 87 normally upon its seat. The diaphragm chamber 88 is supplied through branch conduit 73a from the main pressure fluid supply. The outlet from reservoir 82 is by way of valve 90 which is held against its seat by spring 91 and the pressure against the valve disk from below exerted through the branch conduit 71b. The valve 83 is for the purpose of adjusting the flow of air to reservoir 82 so as to vary the time interval required to open valve 87. This valve 83 is adjustable by means of manual 92 which is within easy reach of the operator. Preferably easily adjusted settings are provided for timing the operation of the pressing machine to ac-

commodate the articles normally being handled. For instance one setting may be for a light article such as handkerchiefs, and another setting for heavier articles such as napkins which would require a longer period. To this end a pair of collars 93 and 94 are provided on the valve casting for valve 83 as shown in Figs. 7 and 9. These collars have stop pins 93a and 94a respectively, the position of which is adjustably fixed by means of set screws such as that shown at 95. The manual has an arm 92a which is shown in the two views as resting against the stop pin 93a for a setting say for heavier articles, such as napkins. By rotating the hand wheel or manual 92 clockwise as viewed in Fig. 7 until the arm 92a engages the stop pin 94a, the setting is quickly changed for light-weight articles such as handkerchiefs.

The timer mechanism is adapted to discontinue the pressing operation when valve 87 is lifted from its seat. The mechanism for this purpose includes a conduit 95 leading by way of check valve 96 and a small reservoir 97 to diaphragm chamber 98. Pressure fluid acting through this diaphragm chamber causes normally open valve 76 to close thus interrupting communication between conduits 71 and 75 and connecting conduit 71 to the exhaust at 99. An adjustable bleed valve 100 communicates with conduit 95.

Means is provided for manually causing termination of pressing engagement between two pressing members and associated with the valve 72. This valve has a manual 72a located handy to the operator. When this manual is in its full line position of Fig. 9 the press has a continuous automatic operation. When the manual is moved about its eccentric mounting to the dot-dash line position of Fig. 9, valve 72 is held against the seat 72b so as to provide communication between conduit 73 and conduit 101 which leads to diaphragm chamber 98.

Operation

When the parts are in the position of Figs. 1 and 2, it is assumed that the manual 72a has been raised to the dash-dot position of Fig. 9 which has caused the bed in registration with head 15 to move downwardly out of engagement with the head after which the turret frame is revolved bringing the other bed into registration position where it remains. To begin automatic operation, the manual 72a is moved to the full line position of Fig. 9. This permits valve 72 to move toward the right under influence of its spring permitting flow of pressure fluid from supply conduit 71 to conduit 73 and valve 74. Since the turret frame is in position registering bed 18 with the head 15, one of the fingers 81 is in engagement with the spring plunger mechanism 78 and valve 74 is open. This permits flow of pressure fluid through conduit 75, normally open valve 76 and conduit 71 to motor 57 which causes an upward stroke of piston 57b and raises bed 18 into pressing engagement with the head 15. At the same time a branch conduit 77c conducts pressure fluid to motor 37 so as to move lever arm 33a to its cocked and latched position shown in Fig. 3. It will be noted in Fig. 3 that the movement of pin 51 upwardly as bed 18 engages head 15, releases lever 58 so that lever arm 33a may carry it toward the right at this time.

Simultaneously with the energization of motors 57 and 37, air pressure travels through the branch 77a, valve 83 and conduit 84 to the timer reservoir 82 and begins to build up pressure in

5 that reservoir. In the meantime the operator has grasped another article from the tray 102 before her for dressing on the bed in the open position. In making the lay she picks up the article by one edge and lays it out toward the rear of the bed 19. She then depresses the pedal 30 which elevates rod 27 and causes clamp 20 to move to the dot-dash position of Fig. 1 thus clamping the rear edge of the article securely to the bed. She then smooths the article out toward the remaining three sides and releases the pedal which permits the clamping bar to return to the normal position shown in full lines in Fig. 1.

15 When the pressure in timer reservoir 82 builds up to the point where the force acting upwardly on diaphragm 85 overcomes the force exerted by diaphragm chamber 88, valve 87 is opened, thus releasing pressure fluid to the diaphragm chamber 98 and moving valve 76 downwardly as shown in Fig. 9. This shuts off all pressure fluid flowing through conduits 75 and 77 and opens conduit 71 to the exhaust at 99. This exhausts motors 57 and 37 and cuts off fluid flow to the timer reservoir 82. The release of pressure below valve 90 of the timer causes a sudden exhaust of pressure fluid from reservoir 82. Evacuation of motor 57 permits the bed 18 to lower out of pressure engagement with the head. This downward movement by means of pin 49 disengages latch 45 from pin 44 which releases lever 33 to the action of springs 39. The lever arm 33a by engagement of the projection 36 then causes the 25 turret frame to be rotated carrying bed 18 out of pressing position and bed 19 into pressing position.

30 As the turret frame begins to move the plunger mechanism 78 swings away from the stem of valve 74 so that this valve closes under the influence of its spring. This cuts off the supply to valve 76 so that when this valve again opens it is not supplied with air until another bed reaches 35 registering position. Air is supplied to the diaphragm chamber 98 only so long as valve 87 is open. This is a comparatively short time but is long enough to provide evacuation of the system. However to insure full evacuation the small reservoir 97 has been provided. This stores just enough pressure fluid to hold the valve 76 closed a short interval after valve 87 closes. This provides additional time which insures full evacuation of the system. The pressure fluid from diaphragm chamber 98 slowly bleeds off through valve 100.

40 45 50 55 60 65 70 75 80 85 90 95 100 If the article which the operator has just dressed on bed 19 in front of her is of different texture than the previous one, as the frame begins to revolve she makes the necessary adjustment of the regulating valve 83 by means of the manual 92. As bed 19 comes into registration with head 15, the pin 51 beneath bed 19 engages pin 63 of lever 58, rotating this lever against the action of the air check 59. At about the same time this post also engages the cam surface 65a of the lever 65. The combined effect is to check or snub the movement of the turret frame until the post 51 lodges in the notch 69. The valve 74 is again opened and the operation as above described is repeated. It should be noted that with the parts in the position of Fig. 4 when the turret frame begins to rotate to change the position of the beds, the rod 51 cams the lever 65 downwardly so as to permit rod 51 to move out of the notch 69.

Should the operator for any reason desire to

cause disengagement of the pressing members other than by operation of the timer, she raises the manual 72a to the dot-dash position of Fig. 9. This moves valve 72 against the seat 72b and establishes communication between conduits 73 and 101. There is sufficient back pressure in the system connected with conduit 73 to fill diaphragm chamber 98 and cause opening of the pressure members as previously described in connection with the timer operation. The registering bed will therefore move out of engagement and the turret frame will be revolved for another operation.

What we claim is:

1. A pressing machine comprising a frame, a stationary pressing member mounted thereon, a turret rotatable in said frame, a plurality of pressing members mounted on said turret for movement alternatively into and out of registration with said stationary pressing member by turret rotation, means for rotating said turret, means for causing pressing engagement between said stationary pressing member and a movable member in registration therewith, a timer for controlling said pressing engagement, said timer including a fluid-receiving reservoir and mechanism operable when said reservoir receives a predetermined fluid load, said pressure-causing means including a fluid motor and a fluid supply line common to said motor and to said reservoir, a normally open valve and a normally closed valve in said supply line in series, means for opening said normally closed valve by movement of one of said movable members into registration, means for closing said normally open valve by operation of said timer mechanism, and means for causing operation of said turret rotating means upon termination of member engagement.

2. A pressing machine comprising a frame, a stationary pressing member mounted thereon, a turret rotatable in said frame, a plurality of pressing members mounted on said turret for movement alternatively into and out of registration with said stationary pressing member by turret rotation, means for causing rotation of said turret including a spring propelled lever, means for loading said spring including a fluid motor, a latch for holding said spring loaded, means for causing pressing engagement between said stationary pressing member and a movable member in registration therewith including a fluid motor, a timer for controlling said pressing engagement, means for supplying fluid to said motor when a movable member is in registration with said stationary member, means for starting said timer coincident with the supply of fluid to said last named motor, means for cutting off fluid supply to said pressing-engagement-causing motor by operation of said timer, and means for releasing said latch upon termination of pressure engagement of two members.

3. A pressing machine comprising a frame, a stationary pressing member mounted thereon, a turret rotatable in said frame, a plurality of pressing members mounted on said turret for movement alternatively into and out of registration with said stationary pressing member by turret rotation, means for rotating said turret including a device operated by a spring, means for loading said spring including a fluid motor, means for causing pressing engagement between said stationary pressing member and a movable member in registration therewith including a fluid motor, a timer including a reservoir adapted to be filled with fluid and an operating device

for causing termination of said pressing engagement and responsive to filling of said reservoir with pressure fluid, a valve closable by said device for stopping fluid supply to said second named motor, and means responsive to movement of a movable member to registration position for supplying fluid to said motors and to said reservoir.

4. A pressing machine comprising a relatively stationary pressing member and a plurality of coacting pressing members mounted for movement consecutively into and out of registration with said stationary member, means for causing movement of one movable member out of registration and movement of another member into registration comprising a spring propelled lever, a spring for operating said lever, a fluid motor for loading said spring, a latch for holding said spring loaded, a fluid motor for causing engagement between said stationary member and a movable member in registration therewith, a timer having a reservoir adapted to be filled with pressure fluid, a supply of pressure fluid for said reservoir and for said motors including in series a normally closed valve and a normally open valve, means for causing opening of said normally closed valve by movement of a movable member into registration position, means for closing said normally open valve responsive to predetermined filling of said timer reservoir with fluid, and means for releasing said latch upon termination of pressure engagement of two members.

5. A pressing machine comprising a frame, a stationary pressing member mounted thereon, a turret rotatable in said frame, a plurality of pressing members mounted on said turret for movement alternatively into and out of registration with said stationary pressing member by turret rotation, means for rotating said turret including a lever, means for causing turret-rotating and return strokes of said lever, a reciprocating device for snubbing turret-rotating movement and having a snubbing stroke and a return stroke, and an operative connection between said device and said lever for causing a return stroke of the former by a return stroke of the latter.

6. A pressing machine comprising head and bed pressing members, fluid actuated mechanism for causing pressing engagement between said members, a valve for terminating pressing action of said mechanism, a servomotor controlling said valve, a fluid actuated timer for controlling said servomotor, a pressure fluid system for operating said mechanism and said timer, a source of pressure fluid normally in communication with said system, and operator controlled means for interrupting communication between said source and said system and for establishing communication between said system and said servomotor.

7. A pressing machine comprising head and bed pressing members, fluid actuated mechanism for causing pressing engagement between said members, a valve for terminating pressing action of said mechanism, a servomotor controlling said valve, a fluid actuated timer for controlling said servomotor, a pressure fluid system for operating said mechanism and said timer, means operable by said timer for momentarily connecting said servomotor with a source of pressure fluid including a conduit system and a check-valve permitting flow toward said servomotor only, and a small reservoir in said conduit system on the

servomotor side of said check valve to increase the period during which said first named valve is held closed.

8. A pressing machine comprising head and bed pressing members, operating mechanism for causing pressing engagement between said members, a timer having operative connections with said mechanism for controlling the operation of said mechanism, said timer including a reservoir adapted to be filled with fluid coincident with operation of said mechanism to cause pressing engagement, a supply of pressure fluid for said reservoir including a control valve, and a plurality of pre-set devices associated with said valve for controlling various positions of said valve.

9. A pressing machine comprising a frame, a stationary pressing member mounted thereon, a turret rotatable in said frame, a plurality of pressing members mounted on said turret for movement alternatively into and out of registration with said stationary pressing member by turret rotation, a plurality of clamps mounted on said turret for clamping articles on said pressing members, one clamp for each of said turret-mounted pressing members, and clamp actuating means mounted on said frame at a predetermined point and adapted to operate each of said clamps when the clamp reaches said point.

10. A pressing machine comprising a frame, a stationary pressing member mounted thereon, a turret rotatable in said frame, a plurality of pressing members mounted on said turret for movement alternatively into and out of registration with said stationary pressing member by turret rotation, a plurality of clamps mounted on said turret, one clamp for each of said turret-mounted pressing members, each clamp being adapted to hold an article on its associated pressing member, means biasing said clamps out of holding position, and operator-operated clamp actuating means mounted on said frame at a predetermined point and adapted to operate each of said clamps to holding position when the clamp reaches said point.

11. A pressing machine comprising a frame, a stationary pressing member mounted thereon, a turret rotatable about a vertical axis in said frame, a plurality of pressing members mounted on said turret for movement alternatively into and out of registration with said stationary pressing member by turret rotation, means for causing pressing engagement between registering pressing members, a plurality of clamps mounted on said turret near said axis, one clamp for each of said turret-mounted pressing members, each clamp being adapted to hold an article on its associated pressing member, means biasing said clamps out of holding position, and operator-operated clamp actuating means mounted on said frame at a predetermined point and adapted to operate each of said clamps to holding position when the clamp reaches said point.

12. A pressing machine comprising a frame, a stationary pressing member mounted thereon, a turret rotatable in said frame, a plurality of pressing members mounted on said turret for

movement alternatively into and out of registration with said stationary pressing member by turret rotation, a plurality of clamps mounted on said turret for clamping articles on said pressing members, one clamp for each of said turret-mounted pressing members, clamp actuating means mounted on said frame at a predetermined point and adapted to operate each of said clamps when the clamp reaches said point, each of said clamps having a part normally positioned for engagement by a part of said clamp actuating means when the associated turret-mounted pressing bed is in out-of-registration position, and said parts being so constructed and arranged that said clamp cams the actuating part harmlessly out of the way when said actuating means is operated before a bed reaches out-of-registration position.

13. A pressing machine comprising a frame, a stationary pressing member mounted thereon, a turret rotatable in said frame, a plurality of pressing members mounted on said turret for movement alternatively into and out of registration with said stationary pressing member by turret rotation, means for causing rotation of said turret, means for causing pressing engagement between said stationary pressing member and a movable member in registration therewith including a fluid motor and a fluid supply therefor, a timer for controlling said pressing engagement, said timer including a fluid-receiving reservoir and mechanism operable when said reservoir receives a predetermined fluid load, means for supplying fluid to said reservoir coincidentally with supply of fluid to said motor, means for shutting off and exhausting said fluid supply to said motor by operation of said timer mechanism, operator-operated means for shutting off and exhausting said fluid supply to said motor, and means for causing operation of said turret rotating means upon termination of member engagement.

14. A pressing machine comprising a frame, a stationary pressing member mounted thereon, a turret rotatable in said frame, a plurality of pressing members mounted on said turret for movement alternatively into and out of registration with said stationary pressing member by turret rotation, means for causing pressing engagement between said stationary pressing member and a movable member in registration therewith including a fluid motor, a timer for controlling said pressing engagement, said timer including a fluid-receiving reservoir and mechanism operable when said reservoir receives a predetermined fluid load, means for supplying fluid to said reservoir and to said motor and comprising a common fluid supply line, a normally open valve and a normally closed valve in said supply line in series, means for opening said normally closed valve by movement of one of said movable members into registration, means for closing said normally open valve by operation of said timer mechanism, and operator-operated means for closing said normally open valve.

JEWEL B. WILLIAMS.
ROBERT C. PAULY.
